UNITED STATES PATENT OFFICE.

JOHN REID, OF YONKERS, NEW YORK, ASSIGNOR TO THE J. L. MOTT IRON WORKS, OF NEW YORK, N. Y.

DESIGN FOR A SEAT-PLATE FOR WATER-CLOSETS.

SPECIFICATION forming part of Design No. 20,346, dated November 18, 1890.

Application filed October 23, 1890. Serial No. 369,136. Term of patent 14 years.

To all whom it may concern:

Be it known that I, JOHN REID, a citizen of the United States, residing at Yonkers, in the county of Westchester and State of New York, have invented or produced a new Design for 5 Water-Closet Seat-Plates, of which the following is a full, clear, and exact specification.

The leading feature of this design is the ornamental shape of the vertical flange, as 10 shown in the accompanying drawings, in which—

Figure 1 is a plan view. Fig. 2 is a front elevation, and Fig. 3 is an end view.

The horizontal flange A is at right angles 15 to the vertical flange B, and both flanges are

rounded at their ends, as shown. The middle portion of the vertical flange B is U-shaped, as at D, and the upper edges are ornamented with leaflet and scroll configurations, as shown.

I claim—

The design of the ornamental shape and configuration of the water-closet seat-plate, substantially as shown and set forth.

Signed by me this 16th day of October, 25 1890.

JOHN REID.

Witnesses:

MAX GOEBEL,
HENRY MORFORD.
